UNITED STATES PATENT OFFICE.

LUCIAN BERRY HAWKINS, OF DANVILLE, INDIANA, ASSIGNOR OF ONE-HALF
TO JOSEPH SCHWARTZ, OF SAME PLACE.

GROCER'S BIN.

SPECIFICATION forming part of Letters Patent No. 399,197, dated March 5, 1889.

Application filed May 21, 1888. Serial No. 274,873. (No model.)

To all whom it may concern:

Be it known that I, LUCIAN BERRY HAWKINS, a citizen of the United States, residing at Danville, in the county of Hendricks and State of Indiana, have invented certain new and useful Improvements in Grocer's Bins; and I do hereby declare the following to be a full, clear, and exact description of the invention, such as will enable others skilled in the art to which it appertains to make and use the same.

This invention relates to improvements in grocer's cans or bins, the object of the invention being to produce a cheap, durable, and efficient grocer's bin having a bottom which may be quickly raised or lowered to adapt the bin to the varying amount of contents—as, for instance, as the contents of the bin are reduced or lowered the supplemental bottom can be raised to bring the contents flush with the top of the bin, where they are easily accessible without the trouble and inconvenience of reaching down inside, as is necessary with cans or bins of ordinary construction.

My invention consists in the special construction and in the combination and arrangement of the several parts of the grocer's bin, substantially as hereinafter described and claimed.

Figure 1 represents in central vertical section a grocer's bin constructed in accordance with my invention; Fig. 2, a perspective view of the same, a portion of the front of the bin being broken away; and Fig. 3 is a central vertical section showing a modified arrangement of the parts.

In the drawings, A represents the side of the bin, having the fixed cross-piece E at the lower end.

B is the movable bottom.

D is a metallic bracket, to which the movable bottom is secured, and C is the screw which passes through the bottom B and bracket D, and operates to raise and lower the bottom B. A packing, b, of any suitable material, (preferably leather,) is secured to the periphery of the movable bottom and insures a tight fit between the bottom B and sides of the can, as is necessary when the material or contents in the can is flour or any finely-pulverized substance. The bar E is fastened permanently across the lower end of the can, and

acts as a support for the lower end of the bottom-adjusting screw C, which is seated in a socket, e, secured to the said cross-piece. This 55 socket may be constructed in halves and engaged with a reduced portion of the screw, as shown at f, Fig. 3, which prevents the possibility of the end of the screw being unseated.

F is a half-cover or permanent section of 60 the can-top, through which the screw C is extended, and which acts as a bearing for the upper end of the screw to retain it in a vertical line. The bracket D, when the screw is at one side of the center of the bin, as shown 65 in Fig. 1, is re-enforced at one side, (its shortest side,) as shown at d², Fig. 1, so as to act as a weight to counterbalance the weight at the opposite side of the bracket or bottom, to prevent the bottom from tipping when the 70 can is filled. This bracket D has an upwardly-projecting boss, d', with a screw-threaded central opening formed therein, through which the screw C extends, and which forms a long bearing therefor.

In Figs. 1 and 2 the screw is shown as located at one side of the center of the bin, extended through the half-cover F, and provided with a hand-wheel, c, by which to operate it, while in Fig. 3 the screw C is shown as 80 directly central with relation to the center of the bin and as considerably shorter than the screw shown in Figs. 1 and 2, and as having a square end to be engaged by a key, h, which is removable. (Shown, for convenience, in 85 Fig. 3 as ready to engage the screw-head.) The construction illustrated in Fig. 3 is preferable, as the screw will be hid from view by the contents of the bin, and when the contents are used or removed sufficiently to expose the top of the screw the key will be applied and the screw turned to bring the contents flush with the top of the bin.

The casing or side A of the bin will be constructed of any suitable material, preferably 95 galvanized iron, and will be of the usual form. The movable bottom B will be secured to the supporting-bracket D by screws d or otherwise. The screw may be located centrally with relation to the center of the casing, or 100 may be located at one side the center, and it may extend through the half-cover F and be provided with a wheel to turn it; or it may be short, as illustrated in Fig. 3, and have a

square end to be engaged by a separate key. Therefore I do not desire to limit myself to either of the exact locations, nor to the exact constructions illustrated in the drawings 5 alone.

The adjustable bottom and its operating mechanism may be readily applied to old bins without much alteration of the bin.

I claim—

- 10 In combination, the sheet-metal open-top tubular body A, having the cross-piece E, secured at the lower end, the socket e, secured to said cross-piece, the vertical screw C, loosely seated at its lower end in said socket, having 15 a square or angular head to receive a similarly-shaped socket of a key, the metal bracket

D, having a screw-threaded boss, outwardly-extended arms mounted upon the screw and adapted to be raised or lowered thereby as the screw is turned, the bottom B, secured to the arms of said bracket, and the flexible annular packing-ring b, secured to the periphery of said bottom B and projecting above the upper face of said bottom, all substantially as shown, and for the purpose set forth. 20

In testimony whereof I affix my signature in presence of two witnesses.

LUCIAN BERRY HAWKINS. [L. S.]
